105,704

DESIGN FOR A SWEATER OR SIMILAR ARTICLE

Ethel F. Kohn, Larchmont, N. Y., assignor to
A. M. Webb & Co., Inc., New York, N. Y., a corporation of New York

Application June 15, 1936, Serial No. 63,318

Term of patent 3½ years

To all whom it may concern:

Be it known that I, Ethel F. Kohn, a citizen of the United States, residing at Larchmont, county of Westchester, and State of New York, have invented a new, original, and ornamental Design for a Sweater or Similar Article of which the following is a specification, reference being had to the accompanying drawing, forming a part thereof.

Figure 1 is a front elevation of a sweater embodying my new design; and

Figure 2 is a rear view with the lower part broken away, of the sweater embodying my new design.

The characteristic feature of my design resides in the band inserted at the arm hole, which band is free hanging and overlies the sleeve, said band matching that at the neckline and contrasting with the sleeves and collar as shown.

The body of the sweater shown in broken lines is conventional in character.

The lining on the drawing is intended for the purpose of distinguishing the elements of the garment illustrated and not for purposes of color.

I claim:

The ornamental design for a sweater or similar article as shown and described.

ETHEL F. KOHN.
